UNITED STATES PATENT OFFICE

ROBERT E. BURK, OF CLEVELAND, AND ELLIOTT B. McCONNELL, OF SHAKER HEIGHTS, OHIO, ASSIGNORS TO THE STANDARD OIL COMPANY, OF CLEVELAND, OHIO, A CORPORATION OF OHIO

APPARATUS FOR ALTERING THE BOILING POINTS OF HYDROCARBONS

Application filed December 1, 1930. Serial No. 499,160.

This invention relates to apparatus for altering the boiling points of hydrocarbons, and more particularly apparatus capable of high-temperature operation; and it is among 5 the objects of the invention to provide equipment adapted to supply heat where wanted at high intensity, and with conservation generally. A further object is the provision of 10 means for apportioning heat requirements in various sections of a converting system. Other objects and advantages will appear as the description proceeds.

To the accomplishment of the foregoing and related ends, the invention, then, 15 consists of the features hereinafter fully described, and particularly pointed out in the claims, the following description and the annexed drawings setting forth in detail an 20 illustrative embodiment of the invention, this being indicative, however, or but one of the various ways in which the principle of the invention may be employed.

In said annexed drawings:

Fig. 1 is an end elevation, partly in section, showing an embodiment of the invention; Fig. 2 is a composite horizontal sectional view, the left-hand portion of such figure being taken on a plane indicated by the line *a*—*a* of Fig. 1, the central portion 25 being sectioned on the line *b*—*b* of the same, the next portion to the right being sectioned on the line *c*—*c*, and the extreme right-hand portion being sectioned on the line *d*—*d* of the same figure, in order to bring out the 30 detail construction at different levels; Fig. 3 is a composite vertical section, the left-hand portion being taken on line *e*—*e* of Fig. 1, and the right-hand portion being taken on line *f*—*f* of the same figure; and Fig. 4 is a 35 sectional detail view on enlarged scale.

Referring more particularly to the drawings, there is shown a furnace setting 2 of suitable masonry or heat-retaining material, and providing a plurality of chambers 3, 45 forming respectively inner chambers receiving upper and lower header manifolds 4, 5, between which are a plurality of tubes 6. At the bottom, such inner chambers communicate with a source of heat, a built-on grate 50 chamber in the case of coal firing for in-

stance, or preferably burners 7 for gas or oil. Such burners are desirably positioned in distributed relation with respect to the chamber, and preferably the manifolds are of X-form whereby to provide a positioning of 55 the tubes in cruciform for at least spaced groups, between which the combustion flame and gases may play. As seen for instance in Fig. 2, an arrangement in which each burner or inlet for combustion gases is 60 placed in the bay between groups of tubes is desirable. At the top, the inner chambers are in communication with an outer chamber 8, between the inner and outer walls of the setting. Such outer chamber in turn, 65 communicates below with stack-flues 9 leading to a stack 10.

Such arrangement as thus seen, provides an inner chamber for high heat application, and means generally for conserving or jacking 70 against heat loss therefrom, while at the same time also making provision for heat requirements of further sections of the equipment. At the top of the inner chambers 3 respectively, each is provided with a preheat- 75 ing coil 11, which connects with the upper manifold 4. Such coils lie between the partitions 12, but extend over to the outer chamber 8, and connect with an initial preheating coil 13 which extends thereabout, and has 80 convenient individually-controlled taps to each coil 11. This coil 13 in turn, is connected by a line 14 to a heat exchanger 15 and thence to the incoming feed line 16, from a suitable source of hydrocarbon supply, the 85 detail of which it is unnecessary to further show.

Each lower manifold 5 connects with a digester chamber 17, which is provided with means for maintaining its temperature at a 90 desired level, ordinarily below that of the tubes 6. This may preferably involve heat insulating jacketing or lagging, or the walls of the setting may be enclosed about such chambers such as to afford protection against 95 undesired temperature drop. With any such means, the rate of heating desired at this point may be maintained, and preferably heat already acquired in the main firing zone. From the digester chamber 17, a con- 100

nection is provided to a further chamber 18, which for convenience may be designated a reactive chamber. Preferably a jet 19 for introduction of additional hydrocarbon material to be acted upon by the highly heated products leaving this stage, is arranged. For instance, gas-oil vapor may be jetted in at this point and be swept along and be acted upon by the highly heated hydrocarbons as coming from the digester chambers. In the additional chamber 18 further action occurs, the temperature of this chamber being maintained, by lagging or other means guarding against material heat loss, at a degree yet relatively high, although ordinarily it is a little lower than that of the digester chamber 17. A draw-off 20 at the bottom of reaction chamber 18 leads to a suitable receiver, the detail of which is immaterial, for the tar or liquid products settling at this stage. A connection 21 at the top leads to heat exchanger 15 and thence to a cooling coil 22, cooled by water or in suitable manner. A jet 23 in the connection 21 is available for use where desired, in introducing cold gas or the like for shock cooling at this point. From the bottom of cooling coil 22, a connection 24 leads to a tower 25, and another connection 26 leads as a bypass, suitable valves being provided, to a drain line 27, or pump line 28, as may be desired. The pump line 28 proceeds to pump 29, and thence to a heat exchanger 30, and on by connection 31 to a heating coil 32 in the outer compartment 8. Such coil in turn, connects by a pipe 33 to a spray head 34 in a flash tower 35. From the top of such tower, a vapor-line 36 goes to a condenser system, the detail of which is immaterial, and requires no further showing. From the bottom of the tower 35 a line 37 proceeds to the heat exchanger 30, and thence to connection 38 leading to a cooling coil 39. From the latter, a pump 40 is arranged to supply a spray-head 41 in the tower 25.

In operation, the manner of usage possible with such apparatus will be readily apparent from the foregoing. Hydrocarbons to be treated, for instance a hydrocarbon gas or vapor, preferably a refinery gas, is introduced by feed line 16, and the relatively cold gas picks up heat in the exchanger 15, thence proceeds through line 14 to the initial pre-heating coil 13, and thence to final pre-heating coil 11, and to manifold 4. With an effective temperature in the inner chamber of about 1700-2100° F., the hydrocarbons are quickly subjected to a cracking or dehydrogenating action, and proceed to collector manifold 5 and reaction chamber 17. In the latter, a lower temperature may be maintained, for instance 1100-1700° F., and polymerization quickly occurs. If additional hydrocarbons, gas oil, etc. be introduced at the point 19, interaction is favored further

in the reaction chamber 18, the temperature of which may be maintained for instance at 1000-1150° F. Heavy tar is drawn off thence by pipe 20, while gasiform or vaporous constituents pass on through pipe 21, heat exchanger 15 and cooler 22, with further condensation. From the cooler 22, the mixed products from the preceding stage pass to tower 25 to be met by a spray of liquid hydrocarbons forwarded by pump 40 from cooler 39. Pump 29 thence returns the liquid mixture from the bottom of tower 25 through exchanger 30, and connection 31 to coil 32, where the temperature is sufficiently raised, that on release through the spray perforations of head 34 in the flash tower 35, constituents will escape as vapor through connection 36 to the condenser system. Desirably, baffling 42 is arranged in such tower, to avoid over-abrupt draw-off.

As an illustrative example:—A refinery gas is passed through the heating coils, attaining a temperature of about 1750° F. in the tubes 6 of the heating system, and thence passes to the chamber 17 and inter-action occurs at a temperature of about 1350° F., the products passing to the chamber 18 and are subjected to a temperature of 1000° F. Heavy tar which separates off is removed by draw-off pipe 20, while the gasiform constituents pass on through the exchanger 15 to the cooler 22, mixed condensate and vapors and gases proceeding thence to tower 25 and are reheated in coil 32 and pass through the flash tower and to the final condenser system, a yield being had of about 10 per cent of motor fuel (having an initial boiling point of 157° F. and a final boiling point of 398° F.), and about 6.5 per cent of heavy tar.

As a further aid to heat pick-up in the intensive heating zone, we prefer to incorporate cores 43 in at least the upper portion of the tubes 6, the diameters being such as to leave a relatively narrow passage between core and tube wall. Beyond such cores, a zone of turbulence is then had, thereby yielding a very effective heat transfer.

By providing a coil 44, advantageously at the bottom of the outer chamber 8, air as supplied by feed pipe 45 from any suitable means, may be heated and thence forwarded to connection 46 to the gas burners or the like, thereby increasing the efficiency of combustion. Similarly positioned in the outer furnace chamber, and preferably above the heater coil 32, is another coil 47, which receives feed from a connection 48 to any desired source, and provides superheated steam through connection 49 to a jet-head 50 in tower 35.

Other modes of applying the principle of the invention may be employed, change being made as regards the details described, provided the means stated in any of the fol-

lowing claims, or the equivalent of such, be employed.

We therefore particularly point out and distinctly claim as our invention:

- 5 1. In apparatus for altering the boiling point of hydrocarbons, a furnace chamber, header manifolds at the top and header manifolds at the bottom thereof, a plurality of connecting tubes in vertical arrangement between said manifolds in bays exposing both sides of the tubes to the heat, and means for conserving the heat of said chamber and for preheating the feed to said tubes, said means including another chamber surrounding said first-named chamber and containing the pre-heating means connecting with the manifold system.
- 10 2. In apparatus for altering the boiling point of hydrocarbons, an inner furnace chamber and an outer furnace chamber surrounding the inner furnace chamber and communicating at the top, a source of heat connecting with the bottom of the inner chamber, a stack-flue communicating with the bottom of the outer chamber, header manifolds at the top and header manifolds at the bottom of the inner chamber, a plurality of connecting tubes therebetween in bays exposing both sides of the tubes to the heat, a preheating coil above the top manifolds and connected therewith, and an initial preheating coil in the outer chamber and connected with the aforesaid preheating coil.
- 15 3. In apparatus for altering the boiling points of hydrocarbons, a furnace chamber, upper and lower manifolds each having corresponding branching arms forming an angle, tubes connecting aligned portions of such manifolds respectively, and heating means at each angle between such sets of tubes and on each side of all tubes.
- 20 4. In apparatus for altering the boiling points of hydrocarbons, a furnace chamber, cruciform upper and lower manifolds forming angles, tubes connecting between said manifolds, and a burner arranged at each angle between the banks of tubes whereby to heat each side of all tubes.
- 25 5. In apparatus for altering the boiling points of hydrocarbons, an inner furnace chamber, an outer furnace chamber surrounding the inner furnace chamber and communicating at its top therewith, upper and lower manifolds in said inner chamber, tubes connecting between said manifolds in bays with a heat supplied to each bay, a preheating coil over the top of said inner chamber and communicating with the upper manifolds, and a preheating coil in the said surrounding chamber communicating with said first-mentioned preheating coil.
- 30 6. In apparatus for altering the boiling points of hydrocarbons, a furnace chamber, cruciform upper and lower manifolds in said chamber, tubes connecting between said man-
- ifolds, and means for conserving heat supplied in said chamber, said means including another chamber around said first-named chamber and communicating therewith and containing a hydrocarbon-preheating coil, and means connecting said preheating coil to said upper manifold.
- 35 7. In apparatus for altering the boiling points of hydrocarbons, an inner furnace chamber and an outer furnace chamber surrounding the inner furnace chamber and communicating at the top, a source of heat communicating at the bottom of the inner chamber, a stack-flue communicating with the bottom of the outer chamber, manifolds at the top and bottom of said inner chamber, tubes connecting between said manifolds, a preheating coil in communication with the upper manifold, and an air-heating coil in said outer furnace chamber and associated with means to supply the source of heat.
- 40 8. In apparatus for altering the boiling points of hydrocarbons, a plurality of inner furnace chambers, an outer furnace chamber surrounding all said inner furnace chambers with communication at the top for said respective inner chambers, upper and lower manifolds in each inner chamber, tubes connecting between said manifolds, and a preheating coil in said surrounding chamber in communication with the tubes in the respective inner chambers.
- 45 9. In apparatus for altering the boiling points of hydrocarbons, a plurality of inner furnace chambers, an outer furnace chamber surrounding all said inner surface chambers, upper and lower manifolds in each inner furnace chamber, tubes connecting said manifolds, preheating coils above said inner chambers and connecting to each upper manifold, and another preheating coil in said outer chamber connecting with the respective first-mentioned preheating coils.
- 50 10. In apparatus for altering the boiling points of hydrocarbons, a plurality of furnace chambers, upper and lower manifolds in each chamber, tubes in each of said chambers connecting said manifolds, said tubes being arranged to present angular bays between groups of tubes, means for supplying combustion gases in the respective bays, and means for conserving heat supplied, said means including another chamber surrounding the first-mentioned chambers and communicating therewith and containing a hydrocarbon-preheating coil for communication with all the tubes.
- 55 11. In apparatus for altering the boiling points of hydrocarbons, an inner furnace chamber and an outer furnace chamber surrounding the inner furnace chamber and communicating at the top, upper and lower manifolds in said inner chamber, tubes connecting said manifolds, a preheating coil connected with the upper manifold, a supply

line for material to be heated connected to said coil, a heat exchanger having an indirect heating passway in the supply line to said preheating coil, a reaction chamber connected to receive products from the lower manifold, and a connection from said reaction chamber through the aforesaid heat exchanger to heat said material by indirect heat exchange.

10 12. In apparatus for altering the boiling points of hydrocarbons, an inner and an outer furnace chamber communicating at the top, upper and lower manifolds in said inner chamber, tubes connecting said manifolds, a 15 preheating coil in communication with the upper manifold, a digestion chamber in communication with the lower manifold, a reaction chamber in communication with said digestion chamber, a jet for the introduction 20 of a fluid in the line between said digestion chamber and said reaction chamber, a flash tower, and means for forwarding the overhead products from said reaction chamber to said flash tower.

25 13. In apparatus for altering the boiling points of hydrocarbons, an inner and outer furnace chamber communicating at the top, upper and lower manifolds in said inner chamber, tubes connecting said manifolds, a 30 preheater coil above the upper manifold and in communication therewith, another preheater coil in said outer furnace chamber and in communication with aforesaid preheater coil, a digestion chamber in communication 35 with said lower manifold, a reaction chamber connected with said digestion chamber, cooling means receiving products from said reaction chamber, a heater coil in the aforesaid outer furnace chamber, a connection 40 from said cooling means to said heater coil, a flash tower, a connection from said heater coil to said flash tower, and means for supplying steam to said flash tower.

45 14. In apparatus for altering the boiling points of hydrocarbons, an inner and an outer furnace chamber communicating at the top, a preheater coil above said inner chamber, upper and lower manifolds in said inner chamber, tubes connecting said manifolds, 50 a digestion chamber in communication with the lower manifold, a reaction chamber in

communication with said digestion chamber, a cooling coil communicating with said reaction chamber, an absorption tower in communication with said cooling coil, a flash tower, means for forwarding products from 70 said absorption tower to said flash tower, and means for supplying steam to said flash tower.

15. In apparatus for altering the boiling points of hydrocarbons, an inner and outer furnace chamber, a preheater coil above said inner chamber, another preheater coil in said outer chamber and leading to said first-named preheater coil, a heat exchanger having an indirect-heating passway through which the feed is passed and thence to said preheater coil in the outer chamber, upper and lower manifolds in said inner chamber, said first-named preheater coil leading to the 80 upper manifold, tubes connecting said manifolds, a digestion chamber in communication with said lower manifold, a reaction chamber in communication with said digestion chamber, a cooling coil, a connection between said reaction chamber and said cooling coil 85 through the aforementioned heat exchanger, an absorption tower in communication with said cooling coil, a flash tower, means including a heater coil in said outer furnace chamber for forwarding products from said absorption tower to said flash tower, and means for cycling liquid through said flash tower and said absorption tower.

16. In apparatus for altering the boiling points of hydrocarbons, a furnace chamber, upper and lower manifolds therein, means for supplying feed stock to said upper manifold, tubes connecting said manifolds, a digester chamber connected with the lower manifold, a reaction chamber connected to receive products from said digester chamber, a heating coil independent of the said tubes, means for forwarding the overhead products discharged from said reaction chamber to said heating coil, and a further chamber into 105 which the hot products from said coil are sprayed.

Signed by us this 15th day of November, 1930.

ROBERT E. BURK.
